UNITED STATES PATENT OFFICE.

CHARLES H. BOECK, OF JACKSON, MICHIGAN.

BURNER FOR OIL-STOVES.

SPECIFICATION forming part of Letters Patent No. 442,567, dated December 9, 1890.

Application filed January 30, 1890, Serial No. 338,664. (No model.)

To all whom it may concern:

Be it known that I, CHARLES H. BOECK, of Jackson, in the county of Jackson and State of Michigan, have invented new and useful Improvements in Burners of Oil-Stoves; and I do hereby declare the following to be a full, clear, and exact description of said invention, reference being had to the accompanying drawings, and to the letters of reference marked thereon, which form a part of this specification.

My invention relates to improvements in burners for oil-stoves; and it pertains more especially to the combination and arrangement of two cylindrical wick-tubes, one located within the other, the mechanism for simultaneously operating the wicks in both of said tubes by a single hand-wheel, the construction and arrangement of the deflectors located above the respective wick-tubes, and the brackets by which such deflectors are supported.

The construction of my invention is explained by reference to the accompanying drawings, in which—

Figure 1 represents a longitudinal vertical section of the burner supported by the inclosing-walls of a heating-stove, the same being by slight modifications equally adapted
30 to be used with a cooking-stove. Fig. 2 represents a top view of the burner with the deflectors removed. Fig. 3 is a detail showing the construction of the receptacle for the wick-adjusting rods. Fig. 4 is a transverse section
35 of the device shown in Fig. 1, taken on a horizontal line just above the lower extremities of the wick-tubes, the parts being shown on a large scale for clearness of illustration.

Like parts are represented by like reference-
40 letters throughout the several views.

A represents the inclosing-walls, by which my burner is supported when the same is used as a heating-stove. The burner, including the respective wick-tubes and attachments, is supported from the walls A through the encircling oil-reservoir B, which is rigidly affixed to the burner, and the supporting-brackets C, which are rigidly affixed to the inclosing-wall A.

50 D is a combustion-chamber.

J and K are cylindrical wick-tubes—one located within the other.

L represents the wicks. The wicks L are each simultaneously adjusted and controlled by a single hand-wheel M, from which motion is communicated to the wicks L through the rod N, pinion O, toothed bar P, horizontal connecting-bar Q, and the wick-adjusting rods S S. The rods S extend upwardly along and on the inside of the inner walls T of the respective wick-tubes J and K. The inner walls T of the respective wick-tubes are bent outward a slight distance, by which a narrow groove or receptacle U is formed in such wall for the reception of the respective rods S, as shown in Figs. 3 and 4, in which grooves said rods are free to move upward and downward as may be required to adjust the wicks. Thin plates or partitions V V are placed inside the wick-tubes J and K in front of the grooves U U and are secured liquid-tight to the inner walls T T of the wick-tubes on both sides of the grooves U U and to the bottoms of the tubes, whereby the oil in the respective wick-tubes is prevented from entering the grooves or rod-receptacles U, the grooves or rod-receptacles U being of course open at their bottoms, whereby said rods are free to move upward and downward as required to adjust the wicks. The plates or partitions V extend upward slightly above the highest point of the oil in the oil-reservoir B, whereby it is impossible for the oil in seeking its level in the wick-tubes to reach a sufficient height to overflow said partitions V and escape through the rod-receptacles U. At a point slightly above the partition V the respective adjusting-rods S are bent outward above said partitions V, and are respectively attached at their ends to thin annular wick-controlling slides b b, which slides bear firmly against the wicks and are free to move upward and downward with them in their respective wick-tubes. The flame from the central wick-tube is deflected outwardly by the central deflector A', while the flame from the exterior wick-tube is deflected outwardly by the annular deflector B'. The deflector A' is centrally supported from the body of the stove by the bracket C' and rod D', while the deflector B' is supported 10

from the bracket C' by the bracket E', both of said deflectors being supported independently of the burner or oil-reservoir, which parts may be readily removed from the stove 5 without disturbing the deflectors.

F' is an exterior annular deflector, by which the width of the exterior flame is limited to the space between it and the deflector B'.

I' is an oil-duct through which the reservoir B is filled with oil.

The wick-tubes J and K are supported in the annular opening of the reservoir B, and free from contact therewith, by the cross-rods c and oil-ducts d, through which oil-ducts 15 the oil is led from the inclosing-reservoir to the respective wick-tubes, as shown in Fig. 2.

G is an annular wall surrounding the exterior wick-tube and at a slight distance therefrom, whereby an air-space H is provided between the wick-tubes and the oil-reservoir, which prevents to a large extent the heat from the wick-tubes being transmitted to the oil-reservoir. 20

Having thus described my invention, what 25 I claim as new, and desire to secure by Letters Patent, is—

1. In an oil-stove, the combination of two annular wick-tubes J and K, located one within the other, each wick-tube being provided with a groove or rod-receptacle U for the reception of the wick-controlling rods S, rods S S, extending upward from the lower end of said grooves or rod-receptacles and connected at their upper ends with annular 30 wick-controlling slides b b within the respective wick-tubes, annular wick-controlling slides b b, horizontal connecting-bar Q, affixed to the lower ends of said wick-controlling rods S, and means for raising and lowering 35 said connecting-bar Q and the therewith-connected wick-controlling rods and wicks, all substantially as and for the purpose specified. 40

2. In an oil-stove, the combination of two annular wick-tubes J and K, located one within the other, each being provided with a groove or rod-receptacle U for the reception of the wick-controlling rods S, rods S S, extending upward from the lower end of said grooves or rod-receptacles and connected at their upper ends with annular wick-controlling slides b b within the respective wick-tubes, annular wick-controlling slides b b, horizontal connecting-rod Q, affixed to the lower end of said wick-controlling rods S, toothed bar P, affixed at its lower end to said connecting-bar Q, pinion O, meshing into the teeth of said bar P, rod N, and hand-wheel M, all substantially as and for the purpose specified. 45 50 55

3. In an oil-stove, the combination, with two concentric wick-tubes located at a distance apart, and an inclosing-wall on which the wick-tubes are supported, of a central disk-deflector A', an outer annular deflector F', supported on the inclosing-wall, an intermediate annular deflector B', between which deflector B' and each deflector A' and F' there is an annular flue or flame-passage, and means consisting of a bracket C', supported on a flange of the deflector F', and a bracket E' 60 and a rod D', connected removably to the bracket C', to which the deflectors A' and B' are respectively attached, whereby the deflectors A' and B' are suspended above the wick-tubes, and the three deflectors so secured 65 to each other are unitedly removable from above the wick-tubes, substantially as described. 70 75

In testimony whereof I affix my signature in presence of two witnesses.

CHARLES H. BOECK.
